[57] CLAIM

The ornamental design for a game adapter cartridge, as shown and described.

DESCRIPTION

FIG. 1 is a perspective view of game adaptive cartridge showing our new design;

FIG. 2 is a front elevation view thereof;

FIG. 3 is a top plan view thereof;

FIG. 4 is a bottom plan view thereof;

FIG. 5 is a rear elevation view thereof; and,

FIG. 6 is a right side view thereof, with the left side view being the mirror image thereof.

The broken line showing of vents, switches and lights is for illustrative purpose only and forms no part of the claim.
